(57) **CLAIM**

The ornamental design for a hanging display with removable signs, as shown and described.

DESCRIPTION

FIG. 1 is a front elevational view of a “hanging display with removable signs” showing my new design;

FIG. 2 is a rear elevational view thereof;

FIG. 3 is a right side elevational view thereof, the left side being a mirror image thereof;

FIG. 4 is a top plan view thereof;

FIG. 5 is a bottom plan view thereof; and,

FIG. 6 is a front right side perspective view thereof, the material shown in phantom is for environmental purposes only and does not form a part of the design.
